US00D896179S

(12) **United States Design Patent** (10) Patent No.: **US D896,179 S**
(45) Date of Patent: ** *Sep. 15, 2020

(54) **POWERED BATTERY CASE**

(71) Applicant: **Jing Yang**, Linhai (CN)

(72) Inventor: **Jing Yang**, Linhai (CN)

(*) Notice: This patent is subject to a terminal disclaimer.

(**) Term: **15 Years**

(21) Appl. No.: **29/668,666**

(22) Filed: **Nov. 1, 2018**

(51) LOC (12) Cl. **13-02**

(52) U.S. Cl.

USPC **D13/119**; D3/294; D13/103

(57) **CLAIM**

The ornamental design for a powered battery case, as shown and described.

DESCRIPTION

FIG. 1 is a left side view of a powered battery case showing my new design;

FIG. 2 is a right side view of the powered battery case;

FIG. 3 is a front view of the powered battery case;

FIG. 4 is a rear view of the powered battery case;

FIG. 5 is a top view of the powered battery case;

FIG. 6 is a bottom view of the powered battery case;

FIG. 7 is a perspective view of the powered battery case;

and,

FIG. 8 is a reverse perspective view of the powered battery case.

1 Claim, 4 Drawing Sheets

FIG. 1

FIG. 2

FIG. 3

FIG. 4

FIG. 5

FIG. 6
